UNITED STATES PATENT OFFICE.

HENRY GROSS, OF CHICAGO, ILLINOIS.

TIME-LOCK.

SPECIFICATION forming part of Letters Patent No 321,894, dated July 7, 1885.

Application filed February 5, 1885. (No model.)

To all whom it may concern:

Be it known that I, HENRY GROSS, a citizen of the United States, residing at Chicago, in the county of Cook and State of Illinois, have 5 invented certain new and useful Improvements in Time-Locks, of which I do declare the following to be a full, clear, and exact description, reference being had to the accompanying drawings, forming part of this specification.

My present invention, which relates to the improvement of time-locks, such as are now commonly used on the doors of burglar-proof safes and vaults, has for its object to provide 15 improved means whereby, in event of accidental stoppage of the time mechanism before the appointed hour for opening the safe, such time mechanism will cease to prevent the movement of the combination-lock, which may 20 then be operated in the usual manner.

To this end my invention consists, primarily, in combining with the usual time mechanism and permutation - lock a suitable lifting-rod for holding the angle-bar of the lock 25 out of engagement with the tumblers, and a movable dogging device, which serves to sustain the lifting-rod and prevents the engagement of the angle-bar with the tumblers so long as the clock mechanism is running, but 30 which, when the clock mechanism stops, can be brought and retained in such position as to permit the lifting-rod to drop and the angle-bar to engage with the notches of the tumblers.

My invention also consists in various details 35 of construction hereinafter described, illustrated in the accompanying drawings, and particularly defined in the claims at the end of this specification.

Figure 1 is a view of my device, partly in 40 side elevation and partly in vertical section on line $x\ x$ of Fig. 2. Fig. 2 is a view in vertical transverse section on line $y\ y$ of Fig. 1. Fig. 3 is a front view of the casing that encloses the clock mechanism, adjacent parts 45 being shown in elevation. Fig. 4 is a rear view of a movable dog and friction-plate in position. Fig. 5 is a view in vertical section on line $z\ z$ of Fig. 3.

A designates the main casing of a permutation-lock having the notched tumblers B, bolt C, link D, and angle-bar E, constructed and

arranged to operate in the usual manner. At a suitable point near the permutation - lock will be placed the time mechanism, which, save in the particulars hereinafter noted, will be of 55 ordinary construction. Upon the back plate, F, of the clock work casing is formed the hub f, whereon is journaled the movable dog G, which may be of disk shape, as shown, and which is provided with a notch, g, in its 60 periphery, and a lug, g', on its outer face for a purpose to be presently explained. Through the hub f passes a shaft, H, of the clock-work, having fixed to its reduced outer end the sleeve h, on which is journaled the expanded 65 hub of the friction plate or disk I, provided with the pin i, that enters a slot, g'', of the movable dog, and serves to connect this dog and the friction-plate together.

From this construction it will be seen that 70 any movement of the shaft H in the direction of the arrow, Fig. 1, will, by reason of the frictional contact between the sleeve h and the hub of the friction-plate I, cause a movement in like direction of this plate and the movable 75 dog until the lug g' of this dog strikes the depending end k of the link K.

Through the clock-work casing, as seen in Fig. 5, passes the lifting-rod L, the upper bent end, l, of which rests upon the periphery of 80 the movable dog G, and the lower end of which is attached, as at l', to the angle-bar E. This lifting-rod, when resting upon the movable dog, serves to retain the angle-bar in such position above the notches of the tumblers that 85 it cannot engage therewith; but if the notches of the tumblers be brought into alignment and the movable dog be turned backward until the notch g is beneath the end l of the lifting-rod, this rod will then drop and allow the angle-bar 90 to engage with the tumblers.

In order to retract the movable dog when the clock mechanism has stopped a suitable lever is employed. The lever shown is composed of the lower arm, M, having the cam-shaped end m, the central hub, m', which receives the journal-pin N, the arm m'', and the link K, pivotally connected to the end of the arm m''. The arm M projects, as shown, within the lock-casing in such position that the 100 cam-shaped end m may be struck and moved backward by the pin b on the face of the outer-

most tumbler of the series, and the link K projects through the casing of the clock-work, and is provided with a depending end, k, adapted to engage with the lug g' of the movable dog, as seen in Fig. 2.

From the foregoing description of the construction the operation will be seen to be as follows, assuming the angle-bar to be out of engagement with the tumblers and the time mechanism set for a desired number of hours: So long as the clock-work continues to move the friction-plate will tend to hold the movable dog in the position shown in Fig. 1, wherein it serves to sustain the lifting-rod, and hence prevents the engagement of the angle-bar with the tumblers. If, however, the clock mechanism should stop, the turning of the outermost tumbler by means of the driving-spindle will cause the pin b to strike the end m of the lever, forcing it backward, and causing the bent end k of the link K to depress the lug g' until it strikes the stop-pin o on the outer face of the clock-work casing. At this moment the notch g of the movable dog will pass beneath the bent end of the lifting-rod, which will thereby be permitted to drop, so as to allow the angle-bar to enter the notches of the tumblers when these have been brought into alignment beneath it.

So long as the clock mechanism is running the angle-bar cannot be made to engage with the tumblers, for the reason that, although the movement of the outermost tumbler will bring the notch of the movable dog beneath the bent end of the lifting-rod, the friction-plate will move the dog forward again before the notches of the remaining tumblers can be brought into alignment beneath the angle-bar.

It will be readily understood that the precise details of construction may be varied without departing from the spirit of my invention. Thus, for example, the movable dog may be other than disk-shaped if desired, although with any form of dog it is desirable that it should be journaled upon a hub formed on the casing, as all strain upon the shaft of the clock-work is thus avoided.

Having thus described my invention, what I claim as new, and desire to secure by Letters Patent, is—

1. In time-locks, the combination, with the clock mechanism and the permutation-lock, of a lifting-rod for holding the angle-bar of the lock out of engagement with the tumblers, a movable dog for sustaining said lifting-rod, and suitable levers for retracting said dog, substantially as described.

2. In time-locks, the combination, with the clock mechanism and the permutation-lock, of a lifting-rod connected with the angle-bar of the permutation-lock, a movable dog for sustaining said lifting-rod, connected with the clock mechanism, and suitable lever mechanism located in position to be moved by the lock-tumblers and to operate the movable dog, substantially as described.

3. In time-locks, the combination, with the clock mechanism and the permutation-lock, of a lifting-rod for holding the angle-bar out of engagement with the tumblers, a movable dog sustained by the main casing, a friction-plate loosely journaled upon the shaft of the clock mechanism and connected with the movable dog, and suitable lever mechanism located in position to be moved by the lock-tumblers and to operate the movable dog, substantially as described.

4. In time-locks, the combination, with the clock mechanism and the permutation-lock, of a lifting-rod for holding the angle-bar out of engagement with the tumblers, a movable dog for sustaining said lifting-rod, journaled upon the main casing, a friction-plate journaled on a shaft of the clock-work, and suitable lever mechanism having an end in position to engage with the movable dog, and a portion in position to be operated by the tumbler, substantially as described.

HENRY GROSS.
